UNITED STATES PATENT OFFICE.

JULIUS W. SMITH, OF MADISON, MINNESOTA.

METHOD OF TREATING AMALGAMS.

1,176,176.

No Drawing.

Specification of Letters Patent. Patented Mar. 21, 1916.

Application filed September 11, 1915. Serial No. 50,184.

To all whom it may concern:

Be it known that I, JULIUS W. SMITH, a citizen of the United States, residing at Madison, in the county of Lac qui Parle and State of Minnesota, have invented certain new and useful Improvements in Methods of Treating Amalgams, of which the following is a specification.

My invention relates to a method of 10 treating amalgams to prevent or delay the setting or crystallization of the same until the operator desires it, in order to enable the operator to have ample time in which to insert the same in the teeth or other purposes 15 to which it is to be applied.

In filling molds, counter-dies, or cavities in teeth with amalgam it is necessary to pack the amalgam in pieces the better to condense or perfectly fill the mold, counter-die, or 20 cavity. If this is not done quickly the last pieces of amalgam used will be in a partial state of crystallization, and thus very difficult to work tight, and much weakened in 25 strength when forced into the mold or cavity. In order to prevent this hardening of the amalgam I take advantage of the physical property of mercury, whereby the same becomes a solid metal at forty degrees Fahrenheit below zero. When the amalgam is 30 freshly prepared and in a soft state, I quickly reduce it in temperature and hold it in said state until I desire to use it. It is preferably divided into small pieces or pellets of the size needed and placed in carbon 35 dioxid snow, or in a cell or other chamber surrounded by carbon dioxid snow; or subjected to carbon dioxid gas, nitrous oxid gas; or any other rapidly expanding gas, which will reduce it to the desired tempera- 40 ture.

As the amalgam is needed for use it is removed from its freezing agent, the temperature quickly rises, the mercury melts and conditions are restored whereby crystallization can take place as an amalgam. It can 45 upon removal from its freezing agent be softened by mild heat or holding between the fingers, and be packed into its mold or cavity which is prepared to receive it. Each succeeding piece will be in a corresponding 50 soft state and a perfect filling can be accomplished.

Having now fully described my invention, what I claim as new, and desire to secure by Letters Patent, is:—

1. The method of treating and using amalgam, which consists in subjecting the same to a freezing agent and holding it in a frozen condition until the application or use of the same is desired.

2. The method of treating and using amalgam, which consists in reducing the temperature of the same until the mercury becomes solid, and then heating the mass to render it plastic and workable when it is 65 desired to use it.

3. The method of treating and using amalgam, which consists in placing the same in a chamber in the presence of a freezing gas or agent and holding it in a frozen condition 70 until it is desired to use it.

In testimony whereof I affix my signature in presence of two witnesses.

JULIUS W. SMITH.

Witnesses:

O. W. SCHULZ,
H. I. THARALDSON.
